UNITED STATES PATENT OFFICE.

CLINTON C. HUMMEL AND JOSHUA E. DEETER, OF CARLISLE, ARKANSAS.

COMBINED MATCH-HOLDER AND TOBACCO-BOX.

1,100,881.

Specification of Letters Patent. Patented June 23, 1914.

Application filed February 21, 1914. Serial No. 820,268.

To all whom it may concern:

Be it known that we, CLINTON C. HUMMEL and JOSHUA E. DEETER, citizens of the United States, residing at Carlisle, in the county of Lonoke and State of Arkansas, have invented certain new and useful Improvements in Combined Match-Holders and Tobacco-Boxes, of which the following is a specification, reference being had to the accompanying drawings.

As every smoker knows, inconveniences are often occasioned, owing to the fact that at the time the pipe or cigarette is wanted, no matches are handy and with this in view, it is the primary object of our invention to provide a simple and efficient construction of tobacco box or pouch the lid of which contains a compartment for holding matches, whereby the smoker may always have a supply at hand.

A further object of the invention is an improved construction of device of this character in which the matches will be kept entirely separate and distinct from the tobacco whereby the latter will not be injuriously affected by either the wood sticks or heads of the matches, while at the same time, the compartment with which the lid is provided is so formed that when the lid is opened, the matches may be easily withdrawn as required.

A still further object of the invention is an improved device of this character which may be very cheaply and easily made and applied to the lids of the conventional type of tobacco boxes or tin at a minimum cost, whereby the device may be used in the nature of an advertisement as it will not add appreciably to the cost of the box.

The invention has for still another object a device of this character in which the bowed strip of metal or other substance which forms the compartment in the top or lid is of such formation that it will serve to assist in holding the lid in closed position, whereby accidental opening and the consequent spilling of the contents are avoided. And the invention also aims to generally improve containers of this character so as to render them more useful and convenient and commercially desirable.

With these and other objects in view as will more fully appear as the description proceeds, the invention consists in certain constructions, arrangements, and combina-

tions of the parts that we shall hereinafter fully describe and claim.

For a full understanding of the invention, reference is to be had to the following description and accompanying drawing, in which,

Figure 1 is a side elevation, partly in section of a tobacco box embodying the improvements of our invention; Fig. 2 is an end elevation thereof, the lid being shown partly open in dotted lines; Fig. 3 is an end view partly in section; Fig. 4 is an enlarged fragmentary sectional view illustrating the manner of forming the match container in the lid; Fig. 5 is an inverted plan view of the lid; and Fig. 6 is a side view thereof partly broken away.

Corresponding and like parts are referred to in the following description and designated in all of the views of the accompanying drawing by like reference characters.

Referring to the drawing, the numeral 1 designates the body portion and 2 the lid of a tobacco box, these parts being of any desired or conventional construction or design, except as hereinafter noted, the lid in the present instance being hinged to the body portion of the box, although it is to be understood that the invention is not limited in this regard.

In carrying out our invention, we take a strip of tin or other metal or suitable substance, as preferred, and we form it into a trough-shaped member 3 closed at one end, as indicated at 4, but open at the other. This trough-shaped member 3 is preferably formed along its side edges with outstanding flanges 5 adapted to be snapped back of or above the spurs 6 which are, in the present instance, formed by punching inwardly through the side flange 7 of the lid 2. In this way, the lid is formed with a match receiving compartment open at one end and closed at the other, and it will be seen that while the lid is in closed position, the match containing compartment will be entirely shut off and separate from the main inferior of the box body, whereby the matches will be kept entirely distinct and separate from the tobacco and all contamination or deterioration of the latter will be prevented.

From the foregoing description, in connection with the accompanying drawings, the operation and practical use of our improved device will be apparent.

Whenever the smoker desires to obtain a supply of the tobacco and opens the lid for that purpose, he at once exposes the opened end of the match containing compartment 5 and can easily shake the matches therefrom to light the pipe or cigarette, as the case may be.

It is to be particularly noted that the device is of very simple construction and one 10 which can be very easily manufactured and applied to tobacco boxes of any conventional or usual type, because it is only necessary to form the latch holding member which is constituted by the trough-shaped member 3 15 with the side flanges 5 or side projections of any character and to then press it into the top or lid 2 after the spurs 6 have been formed in the flange 7 thereof, whereupon the side projections or flanges 5 will snap 20 back of the spurs or inwardly projecting protuberances and the match holding device will thus be securely, although detachably held in position. It is further to be noted that in the closed position of the lid, the 25 latch holding device will engage with the adjacent inner wall of the body portion 1 with sufficient friction to assist in holding the lid in closed position and prevent accidental opening thereof and the consequent 30 spilling of tobacco. Moreover, it will be understood that the matches will be kept dry at all times and will not be liable to become damp from rain or perspiration.

While the accompanying drawing illustrates what we believe to be the preferred 35

embodiment of our invention, it is to be understood that the invention is not limited thereto but that various changes may be made in the combination, arrangement, and proportions of the parts, without departing 40 from the scope of the invention as defined in the appended claims.

What is claimed is:—

1. A box of the character described, including a body portion and a lid therefor, 45 the lid being formed with a marginal flange, and a trough-shaped strip insertible within the lid and formed with side projections, the flange of the lid being formed with inwardly extending projections back of which the 50 first named projections are adapted to snap, for the purpose specified.

2. A box of the character described, including a body portion and a lid therefor, 55 the lid being formed with a flange and the flange having spurs projecting inwardly therefrom, and a trough-shaped member insertible within the lid and formed with side flanges engageable by said spurs, said member being closed at one end and open at the 60 other, for the purpose specified.

In testimony whereof we hercunto affix our signatures in the presence of two witnesses.

CLINTON C. HUMMEL.
JOSHUA E. DEETER.
